UNITED STATES PATENT OFFICE.

WILLIAM A. SCHOENING AND JOSEPH PACHYNISKI, OF CHICAGO, ILLINOIS.

MOUNTING FOR FOLDING WINDOWS AND THE LIKE.

1,272,864.

Specification of Letters Patent. Patented July 16, 1918.

Original application No. 116,614, filed August 24, 1916. Divided and this application filed October 29, 1917. Serial No. 199,094.

To all whom it may concern:

Be it known that we, WILLIAM A. SCHOENING and JOSEPH PACHYNISKI, both citizens of the United States, residing at Chicago, county of Cook, and State of Illinois, have invented certain new and useful Improvements in Mountings for Folding Windows and the like, of which the following is a specification.

10 This invention relates to certain mountings for windows of the multifold type, such as open up passages by a sliding and folding movement, an example of which is shown in our Patent No. 1,245,042, issued 15 October 30, 1917, of which this is a divisional application.

At the outset we wish it noted that the mountings which are herein disclosed are applicable to windows, doors, or like parts, 20 composed of two or more sections arranged to be folded upon each other. For purposes of convenience in description, reference will be made throughout the specification to windows, in explaining the present mountings, 25 although, as before stated, their use may be extended to doors or other folding sections of similar character.

The mountings of our present invention are advantageous in that (1) they are simple and inexpensive to construct and install; 30 (2) they positively guide and securely hold the window sections against accidental displacement; (3) they permit the window to be opened or closed without binding of the parts, and without undue friction; (4) they 35 present a wide clearance when open without projecting the window sections inwardly or outwardly to any considerable extent; and (5) they provide a construction which is 40 adapted to two or more window sections as may be required. These as well as other objects are attained by the improved devices herein described, as will more fully herein-after appear from the specification and 45 claims, and from the accompanying drawings, in which:

Figure 1 is a horizontal section through a four-sash window of the multifold type, (the full lines indicating closed position, and 50 the dotted lines partially open position), such as is adapted to be operated with the mountings of our invention;

Fig. 2 is an enlarged sectional detail of the upper and lower roller mountings for 55 one of the intermediate window sashes;

Fig. 3 is a sectional view similar to Fig. 2,

the sash being represented as in transverse relation to the window frame;

Fig. 4 is a sectional view similar to Fig. 3 of the roller mountings for the sliding end 60 window sash;

Fig. 5 is a detail in elevation showing the upper and lower mountings for the pivoted end window sash;

Fig. 6 is a detail, partly in section, showing the upper and lower mountings for one of the intermediate sashes which is represented as in closed position;

Fig. 7 is a detail, in plan, showing the upper mounting appearing in Fig. 6; the 70 adjoining sash being in angular relation to the sash on which the mounting is carried;

Fig. 8 is a detail of the upper mounting shown in Fig. 5, taken transversely of the 75 head of the window frame;

Figs. 9 and 10 are views of the coöperating bearing plates for the upper and lower mountings, respectively, of Fig. 5; and

Fig. 11 is a plan view of the upper mountings shown in Fig. 5.

The mountings of our invention are particularly suited for use with windows of the kind illustrated in Fig. 1, consisting of a plurality of pivotally connected sashes, say, four in number, designated, respectively, as 85 A, B, C, and D. Preferably the sashes are arranged within a suitable frame which may comprise such parts as a sill 15, side jambs 16 and a head 17. The sashes are constructed substantially alike, and, in the case 90 of windows are formed with stiles 18 and with top and bottom rails 19 and 20 respectively. Hinges 21 serve to interconnect the window sashes and to permit of the folding movements which they are designed to execute. If desired, suitable locks 22 for holding the window sashes closed may be secured to the sill 15 in position to engage with the window sashes, as appears best in Fig. 1.

The sash A is fixedly hinged to one side 100 of the frame, and to permit of swinging movements either inwardly or outwardly, according as the stops are located, and for economy in space as well, the pivotal mountings are secured to the upper and lower rails 105 of the sash in position to engage with bearing elements mounted, respectively, on the frame head and sill. These mountings are best illustrated in Figs. 5 and 8 to 11 inclusive. The lower mounting consists of a 110 member 23 having a tongue 24 and a head 25, the member as a whole being recessed

within the lower sash rail which is suitably mortised for this purpose. The head 25 is rounded on one side as at 26 to conform with a similarly rounded surface on the edge 5 of the stile, enabling the head 25 to lie in flush relation therewith. Through suitable openings formed in the tongue, screws 27 or other appropriate fastening means are entered in the bottom rail of the sash to secure 10 the member 23 in place. On its under side the head is formed with a boss 28 which projects slightly below the under side of the tongue 24 and below the bottom edge of the sash rail as well, this boss being adapted to 15 rest upon a bearing plate 29 (see Fig. 10) suitably secured to the sill. A pin 30 is mounted in the head 25 and is extended downwardly beyond the boss to enter a hole 31 formed in the bearing or journal plate 29. 20 By this means the bottom end of the sash is pivoted upon the sill, being free to swing either inwardly or outwardly unless otherwise prevented, and at the same time it is maintained clear of the sill so as to confine 25 friction, due to swinging, to the engaging surfaces of the boss and bearing plate.

The upper pivotal mounting for the sash A is similar to that described, consisting of a member 32 shaped to provide a tongue 33 30 and a rounded head 34, the whole being recessed within the upper rail of the sash, and suitably secured by screws 35. A pin 36 is mounted in the head 34 and is projected upwardly therefrom through a hole 37 in a 35 top bearing plate 38. The top bearing plate, best shown in Fig. 9, is preferably elongated and is secured to the frame head 17 transversely thereof at a point somewhat above the upper side of the member 32 so as 40 to provide a clearance therebetween. The pin 36 extends out from the head 34 somewhat farther than does the pin 30 from the head 25 for reasons which will shortly appear. A slot or recess 39 is formed trans- 45 versely of the frame head 17 in line with the pivotal mountings for the sash A, and for a width slightly greater than the width of the sash, enabling the sash when swung into transverse position to be raised a distance 50 equal to the depth of this recess. It is manifest, of course, that this upward movement of the sash into the recess 39 will lift the pin 30 of the lower pivotal mounting from its coöperating bearing plate 29, and when 55 so disengaged the lower end of the sash may be laterally shifted until the sill is cleared, whereupon the window can be lowered so as to disengage the upper pivotal pin 36 from the top plate 38 for the purpose of removing 60 the sash from the frame. By a reversal of the movements described, the sash may, of course, be set into the frame, and there maintained securely within its pivotal mountings, the weight of the sash causing it to rest 65 upon the lower bearing plate where both

pivotal pins remain in operative relation within their respective journals. This raising and lowering movement, it should be noted, is only possible when the sash A is swung into a position transversely of the 70 frame at which point it is in alignment with the recess 39 in the frame head.

As previously explained, the various sashes composing the window are interconnected by suitable hinges so as to be capable 75 of folding compactly at one end of the window frame. It is, therefore, desirable that proper supporting and guiding means be provided which shall assist in the movements of the sashes, only one of which— 80 sash A—is fixedly pivoted on the frame. The supports or mountings for each sash are located in the center line of the window—that is, midway between its inner and outer faces, and in line with the pivotal mountings of sash A. The mountings for sashes B, C, and D are of the same general character as those disclosed in our patent referred to, No. 1,245,042, and in a four-sash window, such as we have illustrated by way 85 of example, are situated, one set in the line of juncture between sashes B and C, and the other set at the free end of sash D. The mountings at the juncture of sashes B and C permit of pivotal, sliding, and extension 90 movements, while the mountings on sash D permit of pivotal and sliding movements only. In these respects, they are to be distinguished from the mountings for sash A, 95 which are pivotal only.

The mountings situated at the juncture of sashes B and C, best represented in Figs. 2, 3, 6, and 7, consists of upper and lower parts, the latter of which comprises a U-shaped guideway 40 recessed within the lower rail of the sash B, flanges 41 being provided to hold within the guideway a slide plate 42. The slide plate for purposes of strength and lightness is preferably formed with a body or web 43 on the sides 100 of which are flanges 44 disposed adjacent to the inner sides of the guideway 40 and its flanges 43. The sliding limits of the plate 42 are determined by a slot 45 formed in the guideway within which slot is projected the end of a pin 46 threaded into an opening 47 in the slide plate 42. In the construction shown two such openings 47 are provided to allow an adjustment in the sliding range of the plate 42, if this should be desired, the number of such adjustments, of course, being determined according to the number of openings 47 provided. The end of the slide plate is provided with a rounded head 48 within which is retained a 110 revoluble ball 49 arranged to travel within a grooved plate 50 suitably mounted on the sill. The foregoing description should make it clear that the ball 49 can travel only in a straight line within the grooved plate 50, 115 120 125 130

in consequence of which the plate 42 will be extended longitudinally of the sash by sliding movements within the guideway, as required by the various positions of the sash 5 B as it is folded or unfolded relative to the other sashes.

The upper mounting for the section B comprises a second U-shaped guideway 51 having flanges 52 to retain therewithin a 10 slide plate 53. A pin 54 is likewise threaded through the plate 53 so as to project its end within a slot 55 formed in the guideway for the purpose of determining the sliding limits of the plate within the guideway. At its extremity the slide plate is 15 formed with a rounded head 56 forming a mounting for a pin 57 secured in place in any convenient manner. Upon the pin 57 is mounted a roller 58 formed with an annular 20 peripheral groove 59 and with an annular recess 60 at its upper end. A retaining head 61 is provided on the pin 57 being capable of entering the recess 60, whenever required, to permit of relative shifting 25 movements between the roller and the pin 57. A guide rail 62 is extended horizontally across the window frame in position to engage the grooved portion of the roller 58 so as to hold the same on one side in a 30 fixed line of travel. On its other side a stop 63 is arranged in engaging relation with the roller, thus coöperating with the rail 62 to provide, in effect, an inverted U-shaped 35 guideway within which the roller may travel.

In connection with the upper and lower mountings for the sash B, certain coöperating elements are provided on the sash C, these being best illustrated in Figs. 6 and 7. 40 These elements are in all substantial respects identical, so that a description of only one is necessary. The lower element, shown best in Fig. 7, consists of a plate 64 suitably mounted in operative position on the 45 end of the sash C having at its end adjacent the sash B a curved wall 65 conforming in a measure at least to the rounded end of the head 48 or the roller 58. When the sashes are unfolded to close the window, this wall 50 65 acts as a bumper to engage with the extended head 48 and roller 58 to force the same back into retracted position within their respective guideways.

The sash C which is hinged at one side to 55 the sash B and at the other side to the sash D is adequately supported by the means already described. Upper and lower mountings for sash D are also provided, which resemble the mounting for sash B in many 60 particulars. As appears best in Fig. 4, the lower mounting for sash D comprises a member 66 shaped to provide a tongue 67 and a rounded head 68, the whole being suitably secured to and recessed within the 65 lower end of the sash. Within the head is

mounted a ball 69 adapted to travel within the grooved plate 50. The complementary mounting for sash D at its upper end consists of a member 70 having a tongue 71 and a rounded head 72 carrying a pin 73 on 70 which is mounted a roller 74 formed and mounted similarly to the roller described in connection with Fig. 3. A groove 75 formed annularly of the roller is adapted to receive the guide rail 62, and an annular recess 76 formed in the upper end of the roller enables a head 77 on the end of the pin 73 to enter the roller for a slight distance, thereby permitting a limited shifting movement of the roller upon the pin. The 80 mountings just described in connection with sash D resemble those for sash B, with the exception that they are not extensible; they are designed merely to permit of sliding and swinging movements of the sash D as required for purposes of opening the window.

It will be noted that the mountings of our invention consist of relatively few parts, and that the component elements of each mounting may be handled as a unit during 90 installation. The mountings for the pivoted end sash and the sliding end sash would probably be used on any window consisting of two or more sashes, while the mountings for the intermediate sashes would be duplicated as many times as required for supporting the intermediate sashes. These mountings, as previously explained, lie in the center line of the window and are wholly invisible from either side. The windows 95 are thus enabled to swing either inwardly or outwardly according as desired, the only requirement being that the stops on the head and the sill be properly located. In use, it will be found that the present mountings 100 105 guide the sashes accurately in their sliding and swinging movements, eliminate binding and undue friction, and afford adequate support for the sashes in their various positions.

We claim:

1. In a multifolding window, a pivotal and sliding connection between one of the sashes and the frame consisting of a guideway secured to the sash, a slide plate arranged to move longitudinally within the guideway, a roller mounted on the end portion of the slide plate, the roller being formed with an annular groove therein, a guideway secured to the frame within which 110 the roller may travel, and a projecting portion within the guideway arranged to engage within the annular groove of the roller, the roller being free to move in the direction of its axis upon the slide plate, substantially 115 120 125 as described.

2. In a multifolding window, a pivotal and sliding connection between one of the sashes and the frame consisting of a plate secured to the sash, a roller mounted on the 130

end portion of the plate, the roller being formed with an annular groove therein, a guideway secured to the frame within which the roller may travel, and a projecting portion within the guideway arranged to engage within the annular groove of the roller, the roller being free to move in the direction of its axis upon the slide plate, and means for limiting the extent of such roller movement, substantially as described.

3. In a multifolding window, a pivotal, sliding and extensible connection between one of the sashes and the frame consisting of a grooved plate secured to the frame, a guideway secured to the sash, a slide plate arranged within the guideway and held therewithin against any but longitudinal movements, a ball secured within the end portion of the slide plate and arranged to travel within the grooved plate upon the frame; and means for limiting the range of movement of the slide plate within the guideway consisting of a slot within the guideway, and a member carried by the slide plate arranged to travel within the slot, the position of the member longitudinally of the slide plate being adjustable to vary the range of movements of the slide plate relative to the guideway, substantially as described.

4. In a multifolding window, a pivotal connection between one sash and the frame consisting of aligned pivot pins extended from the upper and lower ends of the sash, the upper pivot pin being extended farther than the lower pivot pin, bearing plates secured to opposite sides of the frame arranged to coöperate with the pivot pins, there being a recess formed in the frame head extending transversely thereof within which the upper bearing plate is located, whereby a clearance is provided between the upper sash end and the proximate bearing plate, the sash being adapted to swing into a position transversely of the frame and into alinement with the recess whereby it may be raised into the recess to disengage the lower pivot pin from its bearing plate preparatory to removing the sash from the frame, substantially as described.

5. In a multifolding window, a pivotal connection between one sash and the frame consisting of members secured to the upper and lower ends of the sash in flush relation therewith, the lower member being provided with a boss depending below the bottom end of the sash, aligned pivot pins extended from

each member, the lower pin being extended from the boss and for a less distance than the upper pivot pin, and bearing plates secured to the frame sill and the other to the frame head, there being a recess in the frame head extending transversely thereof within which the upper bearing plate is located, whereby a clearance is provided between the upper sash end and the proximate bearing plate, the sash being adapted to swing into a position transversely of the frame and into alinement with the recess whereby it may be raised into the recess to disengage the lower pivot pin from its bearing plate preparatory to removing the sash from the frame, substantially as described.

6. In a multifolding window, pivotal, sliding, and extensible connections between one of the sashes and the frame, the said connections being located at opposite ends of the sash and consisting each of members having a connection with the frame and adapted to travel lengthwise thereof, each said connection being also extensible beyond an edge of the sash when the sash is swung to open position, and bumper plates carried by the adjacent sash arranged to engage the extended portions of the said connections when the sashes are brought to closed position whereby the extended portions are retracted to normal position, substantially as described.

7. In combination with a window frame and a sash therewithin normally capable of pivotal movement only with respect to the frame, a pivotal connection between the sash and the frame consisting of aligned pivot pins extended from opposite ends of the frame, bearing plates secured to the frame in co-operating relation with the pivot pins, there being a recess formed in one frame side extending transversely thereof within which one of the bearing plates is located whereby a clearance is provided between the said bearing plate and the proximate sash end, the sash being adapted to swing into a position transversely of the frame and into alinement with the recess whereby it may be shifted into the recess to disengage the remote pivot pin from its bearing plate preparatory to removing the sash from the frame, substantially as described.
